UNITED STATES PATENT OFFICE.

JOHN SCHIES, OF ANDERSON, INDIANA.

DESIGN FOR A BOTTLE.

SPECIFICATION forming part of Design No. 31,706, dated October 24, 1899.

Application filed September 14, 1899. Serial No. 730,506. Term of patent 14 years.

To all whom it may concern:

Be it known that I, JOHN SCHIES, a citizen of the United States, residing at Anderson, in the county of Madison and State of Indiana, 5 have invented and produced a new and original Design for Bottles, of which the following is a specification, reference being had to the accompanying drawings, forming part thereof, and in which—

10 Figure 1 is a perspective view of a bottle, showing my new design; and Fig. 2 is a cross-sectional view on about line 2 2 of Fig. 1.

As shown in the drawings, the leading or material feature consists of the design forming the subject of the accompanying illustration.

15 As shown in the drawings, the bottle is formed with the substantially triangular-shaped body A and the cylindrical neck B, 20 having a rib B' about midway between its ends and a rib or shoulder B² at its juncture with the upper end of the body A.

The body A has the broad flat sides or panels A' and the narrower panels A², breaking the angles between the adjacent panels 25 A', as shown, the panels A² widening at their upper ends and the panels A' narrowing at such ends, merging the body A in the neck B, as shown.

Having described my invention, what I 30 claim as new, and desire to secure by Letters Patent, is—

The design for a bottle, as herein shown and described.

In testimony whereof I have signed my 35 name to this specification in the presence of two subscribing witnesses.

JOHN SCHIES.

Witnesses:

CHARLES F. SKEHAN,
LEANDER K. ROYER.
